UNITED STATES PATENT OFFICE.

FREDERICK JOHN TURNER BELL AND HARDY CECIL BELL, OF ASHTON-UNDER-LYNE,
ENGLAND.

ROTARY LOCK-STITCH SEWING MACHINE.

Application filed December 9, 1921. Serial No. 521,139.

To all whom it may concern:

Be it known that we, FREDERICK JOHN TURNER BELL and HARDY CECIL BELL, subjects of the King of Great Britain and Ireland, and residents of Ashton-under-Lyne, in the county of Lancaster, England, have invented certain Improvements in and Relating to Rotary Lock-Stitch Sewing Machines, of which the following is a specification.

This invention relates to rotary lockstitch sewing machines of that type known as the "two-reel," wherein a bobbin cheese or the like of thread is used as the underthread in the form in which it comes from the manufacturer, without being rewound on spools. (The invention may however also be applied to a machine wherein the underthread has been wound on a spool.) In such machines, as is well known, the underthread is led to the sewing point of the machine, and a rotary hook engages the loop of thread formed by the needle and carries the said loop clear around the casing containing the reel or bobbin of underthread, the loop being then pulled up to form the stitch.

The object of our invention is to provide improved mechanism which will allow of the easy passage of the needle thread loop around the reel or bobbin casing (hereinafter referred to as the bobbin casing) without strain on the said loop; which will from its formation prevent the contamination of the loop thread with lubricating oil; and which will present other advantages to be hereinafter referred to. In carrying it into effect we provide a rotary hook adapted to engage the loop of needle thread and carrying same around the underthread bobbin casing, the axis of rotation of the hook being inclined to the vertical. The plate carrying the bobbin casing is supported by the ring bearing the loop taking hook, and the longitudinal axis of the said bobbin casing is vertical and so placed within the hook bearing ring that its extreme upper edge is approximately on a level with the highest point of the inclined hook ring. The casting off of the needle thread loop from the hook can therefore take place just before the hook reaches the highest point in its rotation, thus allowing the loop to be delivered over the open top of the bobbin casing easily and without jerk, or strain.

A baffle plate is provided to prevent the needle thread loop becoming entangled with the mechanism on the reversal of the latter and special means are also provided for ensuring a free passage of the needle thread loop after it has passed around the bobbin casing and is passing the "anchoring" device used to prevent the rotation of the bobbin casing.

In addition to the above, the invention provides for improved driving means for the lock stitch mechanism.

The invention will now be fully described with reference to the accompanying drawings, wherein:—

Figure 1 is an end elevation of the mechanism, looking from the operative end of the sewing machine table;

Figure 2 is a plan of same, the machine throat plate being removed;

Figures 3, 4 and 5 are details;

Figure 6 is a bottom plan of the machine table, showing driving and other mechanism;

Referring to Figures 1 and 2, 1 is the sewing machine head, 2 the presser foot, and 3 the needle shaft with needle 4. 5 is the throat plate of the machine, fitting on machine table 6 above the lock stitch mechanism. All of these parts 1 to 6 may be of the usual or any convenient construction. To the underside of the machine table 6 is secured a bracket 7 for the purpose of supporting the improved lock stitch mechanism. The latter comprises a hook ring 8 cut away at 9 (Figure 2) to form a hook to take the needle thread loop. The ring 8 is mounted upon a carrier of truncated conical formation 10, which may be cut away as shown in the figures to lessen its weight as much as possible, and which carrier has secured thereto the spindle 11 fitting in a step bearing 12 in the bracket 7 as shown.

The hook ring supports within it, in a circumferential inner recess 13, the plate 14, in which is secured the casing 15, open at its upper end, which is to receive the bobbin of underthread on the central peg or holder 16. The bobbin casing is fitted eccentric to the plate 14. This plate 14, which we will refer to as the race plate, and the bobbin casing 15, are shown in the details Figures 3 and 4 in rear elevation and plan respectively, and in plan in Figure 5, the latter from a point of view at the operative end of

the machine table, as in Figure 2, and Figure 3 and 4 from a diametrically opposite point. It is entirely supported by the hook ring 8, the edge of the latter forming a race 5 for the said hook ring, and is prevented from rotating therewith by the stop 17, shown in Figures 1 and 2, and more clearly in the detail Figure 5, engaging a projection 17^a on the bobbin casing (the direction of 10 rotation of the hook ring being counter-clockwise as viewed in the plan, Figure 2). A further stop 18 prevents rotation of the race plate with its bobbin casing 15 should the mechanism be reversed. 19 is a plate 15 spring secured at one extremity thereof to the wall of the bobbin casing 15, by a screw 19^a as shown. The underthread, in passing from the bobbin contained in the bobbin casing 15, to the sewing point of the machine, passes between the casing and the 20 spring, the latter thus forming a simple tensioning device which may be adjusted and regulated by the tightening or slackening of the screw 19^a. Shallow ribs 20 keep the 25 needle thread loop from becoming entangled in the tensioning spring 19 in its passage around the bobbin casing.

The rotation of the hook ring 8 with hook 9 being counter-clockwise, as viewed in 30 Figure 2, and the hook ring 8 supporting within itself the race plate 14 and the bobbin casing 15 borne by the latter, the continued rotation of hook ring 8 will tend to keep the projection 17^a on the bobbin casing 35 continuously against the stop 17. Means are therefore provided to ensure that when the needle thread loop is to be drawn up to form the stitch there shall be a gap sufficient for the purpose between the parts 17 and 17^a. To this end we fix on the race 40 plate 14 the hemispherical or bulbous projection 21, Figures 1, 2, 3 and 4, this projection being adapted at pre-determined times to be touched on one side by a "toucher" 45 lever 22, attached to a rocking shaft 23 which is actuated in any convenient manner from the needle arm mechanism of the sewing machine.

The rotation of the needle thread loop 50 taking hook on the hook ring 8 is effected by spiral gear wheel 24, on the spindle 11, meshing with a toothed pinion 25 fitted upon the end of and co-axial with the driving shaft 26, shown in Figure 6. This gearing 55 may be enclosed in a casing 11^a, the shaft 26 passing therein through a sleeve 11^b and the boss 11^c provided with packing 11^b thus permitting of the said gearing being run in an oil bath in the casing 11^a. 60 The shaft 26, as well as the toucher lever shaft 23, are supported in brackets on the underside of the machine table, rocking shaft 23 passing through bearings in fixed brackets 28^a, and driving shaft 26 through 65 bearings in adjustable brackets 27 as shown

in Figure 6. The shaft 26 may be made adjustable in a direction transversely of its length by any convenient means. For instance, the heads of the screws 28 may fit within recesses formed in the bracket 27, the screw stem in each case passing through a slot formed at the bottom of the recess. The screws being slackened, transverse adjustment of the shaft 26 may be made within the limits of the length of the slots. 75

This shaft 26 may be driven from the sewing machine arm mechanism in any manner, known in the art. Such driving means are well known and need not be described here.

The operation of the machine is as follows:— The underthread is led from the bobbin in the bobbin casing 15 through tension device 19 to the sewing point as is usual. The needle, descending, forms the needle thread loop in the gap *y*, Figures 2 and 4, 80 and the hook 9 in its rotation engages therewith and carries it around the outside of the hook ring 8. As the hook 9 begins its ascent towards its highest point of its planes of rotation, one side of the needle thread loop slips back from the gap *y* behind the bobbin casing and is spread therearound, the other side being spread around the hook ring 8 by the continued ascension of the hook 9 until, when the latter is at about the 85 position in which it is shown in Figures 1 and 2, the take up of the sewing machine comes into action, drawing the loop smoothly over the top of the bobbin casing. The loop is shown in Figures 1 and 2, 90 at the point where the hook 9 has delivered one side thereof (under the pull of the take up motion) to enable it to continue its rotation, the other side of the loop having passed around the bobbin casing 15. The relative 95 positions of the hook 9 and the bobbin casing 15 at this "casting off" point entirely does away with any strain upon the needle thread loop, and no ribs or spreaders of any kind are necessary—as has hitherto been the case in rotary lock stitch sewing machine mechanism—to ensure a smooth 100 passage of the loop around the bobbin casing. 105

Just before the loop is pulled up by the 110 take up motion the toucher lever 22 comes into action, and, descending upon one side of the projection 21, causes the race plate, with the bobbin casing borne thereby, to move a little around its axis and leave a 115 gap between the projection 17^a on the bobbin casing and the stop 17 for the passage of the loop when being pulled up.

The ratio of a complete needle reciprocation to the rotation of the hook 9 is preferably one to two. In Figure 1 the needle has formed the needle thread loop, the hook 9 in its rotation has engaged the loop and carried it round to the position shown, and the needle is on its upward stroke. Whilst 125

the needle travels upwards to the highest point of its stroke and has partly descended, the hook 9 makes an idle revolution, and by the time it has in its next revolution reached 5 the loop taking position y (Figure 2) the needle has descended and formed the loop for engagement by the hook.

Should the machine be stopped and reversed for any cause just after the needle 10 thread loop has been engaged by the hook 9, there is a danger of the loop slipping off the latter owing to such reversal withdrawing the hook from the loop. To prevent this we provide on the exterior of the bobbin 15 casing and radially thereto at the point shown in Figure 2 and in the detail Figures 3, 4 and 5, a plate 29, over which the needle thread loop passes, to keep it taut upon the hook 9. Reversal of direction of 20 the hook will not with this arrangement draw the hook out of the needle thread loop. After the hook 9 with its engaged needle thread loop has reached a point about 90 degrees from its loop engaging 25 point there is no possibility of the said loop becoming slack on reversal of the machine, as it is then being spread around the outside of the hook ring 8.

We do not confine ourselves to the exact 30 details shown or described, which may be varied within wide limits without departing from the spirit of our invention.

What we claim as our invention and desire to secure by Letters Patent is:—

35 1. In rotary lock stitch mechanism for a sewing machine, a rotatable hook ring cut away at one point to form a loop taking hook, the axis of rotation of the said ring being inclined to the vertical, a race plate 40 having a slight axial motion and supported within the rotatable hook ring for which the race plate periphery forms a bearing, a needle gap in said race plate, means for limiting the axial motion of said race plate, 45 and an underthread bobbin casing support-

ed by the race plate, the longitudinal axis of said bobbin casing being vertical and the highest point in the path of rotation of the inclined hook ring being approximately level with the upper edge of the 50 vertical bobbin casing, and means for rotating the hook ring.

2. In rotary lockstitch mechanism for a sewing machine, a rotatable hook ring cut away at one point to form a loop taking 55 hook, the axis of rotation of the said ring being inclined to the vertical, a race plate having a slight axial motion and supported within the rotatable hook ring for which the race plate periphery forms a bearing, a needle gap in said race plate, means for limiting the axial motion of said race plate, and an underthread bobbin casing supported by the race plate, the longitudinal axis of said bobbin casing being vertical and 60 the highest point in the path of rotation of the inclined hook ring being approximately level with the upper edge of the vertical bobbin casing, means for rotating the hook ring, and a plate fitted exteriorly 65 to the bobbin casing near the needle gap therein and below the hook ring to keep the needle thread taut for a space after the hook engages therewith.

3. In combination with the rotary lock- 75 stitch mechanism for a sewing machine as claimed in claim 1, a coned member bearing the rotatable hook ring, a spindle formed centrally of said cone, and a driving rod for rotating the said spindle and cone with 80 the hook ring, the longitudinal axis of the driving rod and spindle forming a right angle, and spiral gearing on the driving rod meshing with spiral gearing on the spindle.

In testimony whereof we have hereunto 85 set our hands.

FREDERICK JOHN TURNER BELL.
HARDY CECIL BELL.
